DESIGN FOR A COMBINED FRUIT CORER AND SLICER

Henry W. Jacobsen, Cleveland Heights, Ohio

Application September 16, 1941, Serial No. 103,380

Term of patent 7 years

To all whom it may concern:

Be it known that I, Henry W. Jacobsen, a citizen of the United States and a resident of Cleveland Heights, county of Cuyahoga, and State of Ohio, have invented a new, original, and ornamental Design for a Combined Fruit Corer and Slicer, of which the following is a specification, reference being had to the accompanying drawing, forming a part thereof.

Fig. 1 is a perspective view of the combined fruit corer and slicer showing my new design; Fig. 2 is a side elevational view thereof; Fig. 3 is a top plan view thereof; and Fig. 4 is a bottom plan view thereof.

I claim:

The ornamental design for a combined fruit corer and slicer, as shown.

HENRY W. JACOBSEN.
